UNITED STATES PATENT OFFICE.

LEO BITTER, OF BROOKLYN, NEW YORK.

FILING SYSTEM.

Application filed November 12, 1925. Serial No. 68,517.

This invention relates to filing systems, and aims to provide a system for filing elements identified by names or other words both alphabetically and numerically.

5 When data cards, sheets, folders or other elements relating to a large number of different names are to be filed, it has been found more convenient to use a numerical filing system based on numbers arbitrarily allotted to the names than to use an alphabetical filing system. This is because any desired number may be located or inserted in a numerical file with ease even when the file contains a very large number of elements, while alphabetical filing is difficult, where a very large number of names are concerned, owing to the frequent occurrence of identical or similar names. Thus it has been customary to use numerical filing in connection with bank customers, subscription lists, etc. In order, however, to locate the data card or sheet relating to an individual name when the number is not known, it is necessary in all such cases to provide an alphabetical file index to supplement the numerical file. Such indexes are often as large as the file itself, and the expense involved in this duplication has limited the use of the numerical files in spite of their recognized advantages.

20 The present invention, by providing a filing system which is at the same time both numerical and alphabetical, obtains the recognized benefits of numerical filing without the duplication heretofore necessary in providing alphabetical indexes with numerical files.

25 In accordance with the present invention, the numbers allotted to different names for filing purposes are not altogether arbitrary, but are chosen in such manner as to indicate the position of the name in the alphabet. As the result data cards filed numerically in accordance with these numbers are at the same time automatically arranged in alphabetical or approximately alphabetical order so that any card may be located without difficulty in the file when the name but not the number which it bears is known as well as when the number but not the name is known.

30 The invention is carried out by allotting successive series of numbers to successive alphabetical subdivisions, and then applying to each of the elements whose names fall within any one such alphabetical sub-

division one of the numbers of the series allotted to that subdivision. The elements are then arranged in numerical order which necessarily places in juxtaposition all the 60 elements having names falling into the same alphabetical subdivision. The alphabet is subdivided to such extent as may be necessary, in connection with the number of elements to be filed, to throw a comparatively 65 small number of elements, usually less than fifty, within each subdivision. In the file, the alphabetical subdivisions, as well as the series of numbers allotted thereto, may be indicated by guide cards, so that it becomes a simple matter to locate any element whose name is known by merely looking through the elements grouped under the subdivision of the alphabet into which the name falls. At the same time a strictly numerical arrangement is preserved with the consequent advantages in easy filing and selecting in cases where the identifying number is known.

35 A further feature of the invention consists in combining with the above arrangement a system of tabs on the individual elements indicating at once the identifying numbers of the elements.

40 In order that the invention may clearly be understood, I will describe in detail the specific embodiment of it illustrated in the accompanying drawings, in which:—

45 Fig. 1 shows one of the guide sheets used in allotting numbers to the elements to be filed; and

50 Fig. 2 is a perspective view, partly broken away, of a file showing the elements and guide cards arranged in the filing case.

55 In the embodiment of the invention illustrated there are provided one or more guide sheets containing successively arranged alphabetical subdivisions under which are placed successive, but not necessarily consecutive, series of numbers. If the number 60 of elements to be filed is large, a correspondingly large number of guide sheets are necessary, and these sheets may conveniently be bound in the form of a book. The guide sheet shown in Fig. 1 is the one of a set 65 of guide sheets which relates to subdivisions of the letter B. There happen to be thirteen subdivisions of this letter which are arranged in a row near the top of the sheet and identified by numbers from 0 to 12. 70 Under each subdivision are a series of numbers each beginning with the initial B and

having in its hundreds place the figure or figures identifying the subdivision under which it is placed. In the form illustrated, 49 numbers are contained in the series under 5 each subdivision. Thus the first subdivision B contains the numbers from B 001 to B 049, the second subdivision BAK contains the numbers from B 101 to B 149, and the last or thirteenth subdivision BRI, contains the 10 numbers from 1201 to 1249. Similar sheets containing subdivisions of the other letters of the alphabet are provided, although it will be understood, of course, that the number of subdivisions under each letter varies 15 greatly.

The individual elements to be filed, each of which bears a distinguishing name or word, are given numbers obtained from the 20 guide sheets. To give a number to any element, reference is made to the guide sheet bearing the alphabetical subdivision in which the name on this element falls. The first number under this subdivision on the 25 guide sheet is then applied to this element and the number is marked on the guide sheet to indicate that it has been used. All the other elements are given numbers in the same manner, the number chosen being in each case the first number under the appropriate subdivision on the guide sheet which 30 has not been marked to indicate that it has already been applied to another element. In this way each element is given a distinct and different number, the initial letter being 35 for this purpose regarded as a part of the number. At the same time, if the alphabet has been properly subdivided for the particular file in question, some numbers will remain unmarked under each subdivision on the guide sheets, indicating that 40 these numbers are available for use on new elements and may be added to the file from time to time.

While the guide sheets mentioned form a 45 part of the invention and afford a simple and easy means of allotting the proper numbers to the elements, the allotment may be made in accordance with the system described without the use of guide sheets since 50 reference may be had to the elements themselves to ascertain what numbers have already been used.

After a number has been applied to each 55 element, the elements are arranged in the file in numerical order as shown in Fig. 2. In such numerical arrangement the initial letter preceding each number is regarded as a part of the number. This numerical filing results in bringing together groups of elements whose names fall within the same alphabetical subdivision. Such groups are 60 preferably separated and indicated by guide cards 10 as shown in Fig. 2. Each such guide card is provided with a tab 11 on 65 which is marked both the alphabetical sub-

division of the group of elements which it identifies, and an indication of the series of numbers applied to the elements in this group. If, as in the arrangement illustrated, each series of numbers includes numbers 70 which have the same initial and the same hundreds figure, it is sufficient to mark the first number of each series on the appropriate guide card 10, as shown, so that the 75 guide cards bear separated numbers arranged in numerical order.

To further facilitate the use of the system numerically, intermediate numerical guide cards may be introduced between the main 80 guide cards shown. Such intermediate guide cards are, however, an inconvenience in using the system as an alphabetical index. This inconvenience is avoided, in accordance with my invention, by providing the individual elements with tabs indicating their 85 numbers in accordance with the system described and claimed in my co-pending application filed November 13, 1925, Serial No. 68,748. In carrying out this part of the invention each element is provided with a single 90 tab; and the tabs used on the various elements are placed in ten different positions along the upper edges of the elements, are of ten different shapes, and of five different 95 colors. The position of the tab of each element indicates the unit digit of its number, the color of the tab indicates the tens digit of the number (only five tens digits, from 0 to 4, being used in the specific embodiment 100 described), and the shape of the tab indicates the hundreds digit. Since all the numbers allotted to elements falling in the same 105 alphabetical subdivision have the same hundreds digit, it results that the tabs of all the elements behind any one guide card are of the same shape. In consequence the shapes 110 of the tabs assist in alphabetical as well as in numerical searching and refiling, and also indicate readily any mistake in filing.

While I find the arrangement of tabs 115 which I have described most desirable, it will be understood that the system may be modified by using the shape or color or position of the tabs to represent any desired one 120 of the digits of the number.

The number of each element is marked upon the face of the element as shown in connection with the elements B 001 and B 1001 in Fig. 2. In Fig. 2, the distinctive 125 number of each card is shown upon the tab 120 of that card for illustrative purposes only and is not intended to indicate that the numbers need be placed on the tabs.

It will be readily understood that many 130 changes may be made in the specific embodiment shown without departing from my invention. Thus the number of alphabetical subdivisions used must vary with the size of the filing system, the use of an initial letter as part of the identifying number of each 135

element is not in all cases essential, and the system may be used either with identifying tabs on the elements or without them.

What I claim is:—

5. 1. A method of filing elements bearing words, comprising allotting successive series of numbers to successive alphabetical subdivisions, applying to each element a distinctive number of the series allotted to the alphabetical subdivision in which the word on that element falls, and arranging said elements in numerical order in accordance with the numbers so applied. 70
10. 2. A method of filing elements bearing words, comprising allotting successive series of numbers to successive alphabetical subdivisions of each letter of the alphabet, applying to each element the initial letter of the word which it bears and a distinctive 75 number of the series allotted to the alphabetical subdivision of that letter in which said words fall, and arranging said elements serially in accordance with the letters and numbers so applied.
15. 3. A filing system, comprising a series of guides bearing successive alphabetical subdivisions and separated numbers arranged in numerical order, and elements bearing words and distinctive numbers and arranged between said guides in such manner that the elements behind each guide bear words falling in the alphabetical subdivision marked on the guide and numbers between the number on said guide and the number 80 on the succeeding guide. 90
20. 4. A filing system, comprising elements each bearing a word and arranged in successive groups corresponding with alphabetical subdivisions within which their words fall, the elements in the successive groups being identified by consecutive numbers of successive series of numbers. 85
25. 5. A method of filing elements bearing words, comprising allotting successive hundreds to successive alphabetical subdivisions and applying to each element a distinctive number within the hundred allotted to the subdivision in which the word on that element falls. 95
30. 6. A filing system, comprising a plurality of elements each bearing a word, and a distinctive number one portion of which indicates the alphabetical subdivision under which the word on that element falls, said elements being arranged in order according to their numbers. 100
35. 7. A method of filing elements bearing words, comprising allotting successive series of numbers to successive alphabetical subdivisions, applying to each element a distinctive number of the series allotted to the alphabetical subdivision in which the word on that element falls, arranging the elements in numerical order in accordance with the numbers so applied, and separating the ele- 105
- ments relating to different alphabetical subdivisions by guides indicating such subdivisions and the series of numbers allotted to them. 110
40. 8. A filing system, comprising elements bearing words and each having a distinctive number a portion of which indicates the alphabetical subdivision into which the word on that element falls, and each having a tab whose shape indicates said portion of its number. 115
45. 9. A filing system, comprising elements bearing words and each having a distinctive number a portion of which indicates the alphabetical subdivision into which the word on that element falls, and a tab which by its shape, color and position, indicates the complete number applied to that element. 120
50. 10. A filing system, comprising elements bearing words and each having a distinctive number a portion of which indicates the alphabetical subdivision under which the word on that element falls, and a tab which by its shape indicates said portion of the number of that element, and by its color and position indicates the remainder of said number. 125
55. 11. A filing system, comprising elements bearing words and each having a distinctive number, the hundreds portion of which indicates an alphabetical subdivision into which the element falls. 130
60. 12. A filing system, comprising elements bearing words and each having a distinctive number, the hundreds portion of which indicates an alphabetical subdivision into which the element falls, and each element having a tab which by its shape indicates the hundreds portion of the number of that element and by its color and position indicates the tens and unit digits of that number. 135
65. 13. A filing system, comprising elements each bearing a word and arranged in successive groups corresponding with the alphabetical subdivisions within which their words fall, the elements in the successive groups being identified by consecutive numbers of successive hundreds. 140
70. 14. A filing system, comprising elements each bearing a word and arranged in successive groups corresponding with the alphabetical subdivisions within which their words fall, the elements of the successive groups being identified by consecutive numbers between 1 and 50 of successive hundreds. 145
75. 15. A filing system as claimed in the preceding claim in which each element is provided with a tab which by its shape indicates the hundreds digit of the identifying number of that element, by its color indicates the tens digit of said number, and by its position indicates the unit digit of said number. 150
80. 16. A filing system, comprising a guide 155

- sheet bearing successive alphabetical subdivisions and successive series of numbers associated with said subdivisions, and individual elements, each bearing a word falling within one of said alphabetical subdivisions and one of the numbers associated with that subdivision on the guide sheet, a different one of said numbers being applied to each element.
- 10 17. A filing system, comprising a guide sheet bearing successive alphabetical subdivisions and successive series of numbers associated with said subdivisions, and individual elements, each bearing a word
- 15 falling within one of said alphabetical subdivisions and one of the numbers associated

with that subdivision on the guide sheet, the number allotted to each element being deleted on the guide sheet.

18. A numerical filing system consisting of a series of elements identified by a series of numbers and each having a tab, in which the tabs of the elements are of ten different colors and in ten different positions on the elements, the position and color of the tab of each element indicating respectively the unit and tens digit of the number identifying that element, and thus indicating its position in the series.

In testimony whereof I have hereunto set my hand.

LEO RITTER.
